UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

INTEGRAL MEANS FOR REINFORCING METALLIC PLATES.

Application filed September 3, 1926. Serial No. 133,434.

My invention relates to means of reenforcing a metallic plate by forming integral corrugations, embossments or ribs therein and resides in the particular and peculiar configuration and relation of the corrugations to obtain certain desired results.

An object of the invention is to form and arrange a plurality of corrugations in a metallic plate so as to obtain a desired proportion between strength, rigidity and resiliency.

Another object is to obtain this result with the least amount of raw material and to provide a finished article of the least possible weight consistent with strength requirements.

Another object of the invention is to obtain the desired strength, rigidity and resiliency by forming a metallic plate with integral embossments, each having a wide end and a narrow end positioned with their wide ends oppositely disposed, the wide ends of the embossments being divided by ribs extending toward the middle of the embossments.

Another object is to provide such a corrugated metallic plate which can be formed by pressing it (when heated, if necessary) between dies which move toward each other in one direction only.

The construction may be used wherever a strong, resilient panel is desired, but is especially adaptable for railway car structures, such as end walls, side or end doors, hopper doors, floors, roofs, etc., and while I have shown and claimed herein the construction used as an end wall of a railway car, it is my intention to file other applications for patents covering the construction used in other railway car structures.

It is well known that the end walls of railway cars are more likely to be broken or otherwise injured than the side walls. This is due to the inertia thrusts and pressures caused by the shifting of the cargoes when the train starts or stops. These thrusts may be local, tending to distort the end in some particular spot, as, for example, when a piece of piping or lumber shifts lengthwise imparting a blow against the end wall of the car; or there may be a general tendency to break out the end wall as a whole or tear it away from the framing. For the purpose, therefore, of greater strength and durability, car ends have been constructed of metal plates corrugated or formed with ribs to impart the desired strength, rigidity and resiliency. My

construction is especially adaptable to end walls for railway cars (of any type) because it has the strength to resist the continuous pounding of the shifting loads thereon and has the resiliency necessary to absorb these numerous shocks without distortion. Distortion of an end wall might bend the brake mast, thereby causing interference with the operation of the hand brake mechanism. Furthermore, such distortion might reduce the end ladder clearance beyond that prescribed by the Interstate Commerce Commission. When made of several plates secured together the end wall can be made stronger where greater strength is required. A wooden inside lining is required in a railway house car for blocking the lading to and for compliance with the requirements of the Bureau of Explosives of the American Railway Association. Such a wooden lining can be easily applied to my construction.

In the drawings:
Fig. 1 shows the end wall of a railway car with my device applied thereon.
Fig. 2 is a section on line 2—2 of Fig. 1.
Fig. 3 is a section on line 3—3 of Fig. 1.
Fig. 4 is a section on line 4—4 of Fig. 1.
Fig. 5 is a section on line 5—5 of Fig. 1.
Fig. 6 is a detail of a plate reenforced by my arrangement of corrugations.

Fig. 7 is a section on line 7—7 of Fig. 6.
Fig. 8 is a section on line 8—8 of Fig. 6.
Fig. 9 is a section on line 9—9 of Fig. 6.
Fig. 10 is a section on line 10—10 of Fig. 6.
Fig. 11 is a section on line 11—11 of Fig. 6.

The end wall structure comprises a panel composed of one or more metal plates with my particular embossments formed therein.

In Figs. 1 to 5, inclusive, the embossed plates 1, 2 and 3 extend from top to bottom of the end wall and may be formed with integral flanges 4 along the vertical edges of the outer plates which overlap and are secured to the side walls 5 of the car by any suitable means. The top edge of the plate 100 is secured beneath the fascia boards 7 and the meeting edges of the plates overlap and are secured together by rows of rivets 8 and the lower edges of the plates are secured to the end sill 9.

Fig. 6 shows a form of the invention applied to a gondola type of car, wherein only one plate is used to form the end panel which extends from side to side of the car and may be provided along the vertical edges with

flanges which overlap and are secured to the side walls by any suitable means. The top edge of the plate is secured to the top chord by rivets, while the lower edge is secured by rivets to the end sill.

The plate is provided with embossments or corrugations which have a wide end 20 and a narrow end 21 with every other embossment positioned with its wide end adjacent the narrow ends of the embossments positioned therebetween so that the embossments are positioned with their wide ends alternately disposed. The adjacent sides of adjacent embossments are substantially parallel and preferably spaced apart distances 23 equal to their width of the narrow end, as shown in Fig. 6. In the form shown in Fig. 1 the sides of the adjacent embossments are parallel and spaced apart distances equal to their width adjacent the middle 24 of the embossments.

Each wide end of the embossments is divided by a rib 25 or corrugation which extends toward the middle of the embossment 25 and preferably decreases in width and depth from the ends of the embossments.

When the embossments are positioned vertically, their maximum depth is located about one-third up from their lower ends, and when 30 the embossments are positioned horizontally their maximum depth is adjacent their middle.

While the embossments are shown pressed outwardly it is understood that they may be 35 pressed inwardly or partially inwardly and partially outwardly from the original plane of the plate, or the embossments may be placed in any position, for instance, vertically, horizontally or diagonally. The plates 10 may be connected on vertical or horizontal lines and applied to any type of railway car.

The various contours of the corrugations are preferably such that the lengths of the center lines of the metal at every cross section 45 of the corrugated plate normal to the corrugations are equal.

At the plane where the embossments begin to terminate into the original plane of the plate (5—5 of Fig. 1 or 9—9 of Fig. 6) the 50 divided portions 30—30 of the wide end of the embossments; the dividing rib 25; the narrow end of adjacent embossments 21 and the spaces 23 between adjacent embossments are all equal in width and preferably also 55 equal in depth so as to form a sinuous configuration of considerable elasticity and resiliency. Such a construction also obtains great strength for the amount of metal used because the neutral plane is midway between 60 the bounding planes of the embossments. The contour of the embossed plate at one plane where the embossments begin to merge into the plate is substantially the same as at the corresponding plane at the other end of 65 the embossments.

The maximum pressure and stress on a car end wall is about two feet above the floor and adjacent the middle of the car. The corrugations are a series of parallel beams and when positioned vertically the lower ends of 70 the beams are supported by the underframe which is the backbone of the car and the upper ends are supported by the end plate. A beam should have its maximum strength adjacent its point of maximum stress, therefore, I prefer to have the strongest part of the individual corrugation, as well as the entire end wall, about two feet from the floor or about one-fourth the length of the corrugation, therefore, the embossments are deeper 80 adjacent this line, the place of maximum depth preferably being where the division of the wide end begins.

In an application for patent Serial No. 133,433, filed September 3, 1926, I have disclosed and claimed the embossment with relatively wide and narrow ends having the wide ends divided, and in still another application for patent Serial No. 133,435, filed September 3, 1926, I have disclosed and claimed such 90 a structure in combination with other elements.

The accompanying drawings illustrate the preferred form of the invention, though it is to be understood that the invention is not 95 limited to the exact details of construction shown and described, as it is obvious that various modifications thereof within the scope of the claims will occur to persons skilled in the art.

I claim:

1. A metallic plate formed with a plurality of parallel embossments, each having a wide end and a narrow end, said embossments positioned with their wide ends alternately disposed, said wide ends being divided by ribs extending toward the middle of the embossments.

2. A metallic plate formed with a plurality of parallel embossments, each having a wide end and a narrow end, said embossments positioned with their wide ends alternately disposed, said wide ends being divided by ribs which decrease in depth and width toward the middle of the embossments.

3. A metallic plate formed with a plurality of parallel embossments, each having a wide end and a narrow end, said embossments positioned with their wide ends alternately disposed, said wide ends being divided by ribs extending toward the middle of the embossments, at a plane, where the embossments begin to terminate into the plate, said divided portions, said ribs, said narrow ends and the spaces between adjacent embossments are all 120 equal width.

4. A metallic plate formed with a plurality of parallel embossments, each having a wide end and a narrow end, said embossments positioned with their wide ends alternately dis- 130

posed with their adjacent sides substantially parallel, said wide ends being divided by ribs extending toward the middle of the embossments, at a plane, where the embossments begin to terminate into the plate, said divided portions, said ribs, said narrow ends and the spaces between adjacent embossments are all equal in width.

5. A metallic plate formed with a plurality of parallel embossments increasing in depth toward their middle, each having a wide end and a narrow end, said embossments positioned with their wide ends alternately disposed with their adjacent sides substantially parallel, said wide ends being divided by ribs extending toward the middle of the embossments, at a plane, where the embossments begin to terminate into the plate, said divided portions, said ribs, said narrow ends and the spaces between adjacent embossments are all equal in width.

10. A metallic plate formed with a plurality of parallel embossments increasing in depth toward their middle, each having a wide end and a narrow end, said embossments positioned with their wide ends alternately disposed, said wide ends being divided by ribs extending toward the middle of the embossments, the lengths of the center lines of the 15 metal of every cross section of the embossed plate being equal between the planes where the embossments begin to terminate into the plane of the plate.

15. A metallic plate formed with a plurality of parallel embossments increasing in depth toward their middle, each having a wide end and a narrow end, said embossments positioned with their wide ends alternately disposed, said wide ends being divided by ribs 20 extending toward the middle of the embossments, at a plane, where the embossments begin to terminate into the plate, said divided portions, said ribs, said narrow ends and the spaces between adjacent embossments are all 25 equal in width, the lengths of the center lines

of the metal of every cross section of the embossed plate being equal between the planes where the embossments begin to terminate into the plane of the plate.

8. A metallic plate formed with a plurality 50 of parallel embossments, each having a wide end and a narrow end, said embossments positioned with their wide ends alternately disposed, said wide ends being divided by ribs extending toward the middle of the embossments, and adjacent their middle said embossments are spaced apart distances equal to their width.

9. A metallic plate formed with a plurality 55 of parallel embossments, each having a wide end and a narrow end, said embossments positioned with their wide ends alternately disposed, said wide ends being divided by ribs extending toward the middle of the embossments, at a plane, where the embossments begin to terminate into the plate, said divided portions, said ribs, said narrow ends and the spaces between adjacent embossments are all 60 equal in width and also adjacent their middle said embossments are spaced apart distances equal to their width.

10. A metallic plate formed with a plurality 65 of parallel embossments increasing in depth toward their middle, each having a wide end and a narrow end, said embossments positioned with their wide ends alternately disposed, said wide ends being divided by ribs extending toward the middle of the embossments and adjacent their middle said embossments are spaced apart distances equal to 70 their width.

11. A metallic plate formed with a plurality 75 of parallel embossments increasing in depth toward their middle, each having a wide end and a narrow end, said embossments positioned with their wide ends alternately disposed, said wide ends being divided by ribs extending toward the middle of the embossments. 80
